CORING APPARATUS

John C. Stokes, Houston, Tex., assignor to Reed
Roller Bit Company, Houston, Tex., a corpora-
tion of Texas

Application December 13, 1948, Serial No. 64,924

10 Claims. (Cl. 255—72)

1

This invention relates to new and useful improvements in coring apparatus and more particularly to improved means for mounting the inner core-receiving barrel of such apparatus.

In the conventional core-taking apparatus of the type wherein an inner core-receiving barrel is carried within an outer barrel and is run into the well bore with the drill stem, it is customary to mount the inner core-receiving barrel so that it is freely rotatable within the outer barrel during the coring operations. It is, of course, desirable that the core barrel be mounted in a bearing assembly which will not only permit free rotation but which will also take the longitudinal or end thrust to which the inner core barrel may be subjected. Various methods and means of mounting the inner core barrels are in general use but in all such arrangements in which the bearings function as upper and lower end thrust bearings, it has been necessary to locate the bearing assembly at the upper end of the core barrel at a spaced distance from the core bit. Because of this location of the bearing assembly, the core barrel must be removed from the upper end of the apparatus, thereby requiring that the connection between the apparatus and the drill pipe be broken. Further, with the bearing assembly at the upper end of the inner core barrel, the core barrel must be fitted with relatively close tolerances between the said bearing assembly and the core bit at the lower end of the apparatus, thereby complicating the structure and increasing the expense of manufacture.

It is, therefore, one object of this invention to provide an improved mounting for the inner core barrel of a core-taking apparatus wherein the supporting bearing assembly is disposed nearer the lower end of the core barrel, whereby the necessity for the close manufacturing tolerances heretofore required is eliminated and also whereby the core barrel may be readily removed from the apparatus by merely removing the core drill and without having to break the upper connection.

An important object of the invention is to provide an improved mounting for the inner core-receiving barrel of a core-taking apparatus which mounting includes a double set of ball bearings located at the lower portion of the barrel for rotatably supporting the barrel and for taking longitudinal end thrust, the upper end of said barrel being aligned by a simple aligning bearing member, whereby manufacturing is simplified since the necessity for close tolerances is eliminated.

A further object of the invention is to provide a further object of the invention is to provide

an improved apparatus, of the character described, wherein the double ball bearing assembly on which the core barrel is rotatably supported is confined within a bearing housing, with said housing being disposed within the lower portion of the core-taking apparatus adjacent the core bit, whereby disconnection of the bit allows the core barrel to be readily removed from the outer barrel of said apparatus.

10 Still another object of the invention is to provide an improved bearing assembly for mounting an inner core-barrel within the outer barrel of a core-taking apparatus, said assembly including upper and lower ball bearings and having suitable packing means for sealing off at the ends of the bearing assembly, together with simplified means for mounting said assembly against upward and downward displacement within the apparatus.

Other objects and advantages more or less 20 ancillary to the foregoing and the manner in which all the various objects are attained will appear in the following description, which considered in connection with the accompanying drawings, sets forth the preferred embodiment of 25 the invention.

In the drawings:

Figure 1 is a longitudinal sectional view of a core-taking apparatus, constructed in accordance with the invention,

30 Figure 2 is an enlarged longitudinal sectional view of the lower portion of the apparatus and showing the improved mounting for the inner core barrel, and

Figure 3 is a horizontal cross-sectional view 35 taken on the line 3—3 of Figure 2.

In the drawings, the numeral 10 designates the lower portion of a drill pipe which has a sub 11 connected to its lower end. The core-taking apparatus is connected to the drill pipe through the 40 sub 11, and, as is clearly shown in Figure 1, said apparatus includes an outer barrel 12 which is welded or otherwise secured to the lower end of the sub. The lower end of the barrel 12 is connected within the upper end of a drill collar 13, and this connection is also illustrated as a weld, although if desired it may be threaded. The 45 lower end of the drill collar 13 is formed with the usual threaded pin 14, whereby a core bit 15 may be connected thereto. It will be evident that upon rotation of the drill pipe 10, the outer barrel 12, drill collar 13 and core bit 15 will be rotated.

The core bit 15 may be of any desired construction and, as shown in Fig. 2, has a central or axial bore 16 which bore is reduced at its lower 55 portion, as indicated at 16a, whereby an internal

shoulder 17 is formed within the bit. Suitable cutters 18 are mounted on the lower portion of the bit and vertical fluid passages 19, which extend through the body of said bit, direct fluid onto said cutters during the coring operation. A core catcher 20, which may be of ordinary construction, is supported upon the internal shoulder 17 within the bore of the bit, and includes pivoted fingers 21 which are normally urged inwardly into the bore. The body of the core catcher is generally sleeve-like and has its upper portion reduced, as indicated at 20a, whereby the exterior surface of the core catcher body is spaced from the bore 16 of the core bit body 15.

A suitable protector sleeve 22 is initially suspended within the bore of the bit and is prevented from upward movement through the bit by means of projections 23 on its external surface. The body of the protector is provided with slits 24 and when a sufficient force is exerted against the lower end of the protector, the projections 23 may flex inwardly, thereby permitting the protector to move upwardly within the bit. Downward movement of the protector 22 is prevented by the engagement of the core catcher fingers 21 with annular grooves or notches 25 formed in said protector. The protector 22, as well as the core catcher 20 and the core bit 15, are all parts of usual construction, and the particular details thereof are subject to variation.

An inner core-receiving barrel 26 extends axially within the outer barrel 12 and also within the drill collar 13 and has its lower end terminating adjacent the upper end of the core catcher 20. The upper end of the barrel is closed by a valve cage 27 which is threaded into this upper portion, and a suitable ball check valve 28 is mounted within the cage. The valve cage or body 27 is formed in two pieces which are connected by a threaded connection, and an annular alignment bearing 29 is mounted within an annular groove 30 formed in the upper end of the valve cage or body 27. The alignment bearing may be constructed of neoprene or other suitable material and has its outer peripheral surface formed with ribs or enlargements which are adapted to abut the bore 12a of the outer barrel 12. The alignment member 29 functions to axially align the upper end of the inner barrel 26 within the outer barrel 12, while permitting a downward flow of fluid through the annular space between said barrels. The valve cage or body 27 has an axial bore 27a which communicates with the area adjacent the valve seat 28a which is engaged by the ball valve 28. A vent tube 32 threads into the bore 27a and extends upwardly therefrom.

It will be apparent that the ball valve 28 is downwardly closing and will prevent the admission of any fluid which may be flowing downwardly through the drill pipe into the core-receiving barrel 26. However, if the pressure within the core barrel 26 exceeds the pressure acting against the upper end of the ball valve 28, said valve may be unseated to permit a venting of the upper end of the barrel.

For rotatably supporting the lower portion of the inner barrel 26, said inner barrel is provided with an external annular flange 33 which may be formed integral with said barrel. The flange 33 is located nearer the lower portion of the barrel 26 and its upper surface provides an upper bearing raceway 34 while its lower surface forms a lower bearing raceway 35. Upper bear-

ings 36 are supported upon the upper raceway 34, while lower bearings 37 engage the lower raceway 35. The bearings 36 and 37 are retained in position by an annular bearing housing 38 which has the upper end 39 of its bore reduced to surround the barrel 26 above the upper bearings 36. Within the bore, the housing has an annular curved surface 40, which confines the upper ball bearings 36. A suitable packing ring 41, which may be of the O-ring type, seals off between the barrel 26 and the housing 38.

The lower portion of the bearing housing 38 telescopes and is suitably secured to the upper end of a tubular sleeve or casing 42. The upper end of this casing or sleeve has the lower bearings 37 supported thereon, whereby this upper edge, indicated at 42a, forms a raceway for the lower ball bearings 37. The sleeve or casing 42 extends downwardly and has its lower end insertable within the bore 16 of the core bit. An external annular shoulder 43 which is downwardly facing, is formed on the lower portion of the sleeve or casing 42 and abuts an internal shoulder 15a provided within the core bit, the engagement of the external shoulder 43 with the internal shoulder 15a functioning to limit the downward movement of the sleeve or casing 42. For confining the bearing assembly against upward movement with respect to the core bit and outer barrel, a plurality of spacing ribs 44 are welded or otherwise secured to the intermediate portion of the sleeve or casing 42. Each rib is formed with an upwardly facing shoulder 45 at its lower end, and this shoulder is adapted to abut the lower end 13a of the drill collar 13. Thus, it will be seen that when the inner barrel 26 and its lower bearing assembly are in position within the outer barrel and drill collar, said inner barrel and bearing assembly is confined against upward or downward displacement with respect to the outer barrel and drill collar. Upward displacement is prevented by engagement of the shoulder 45 of the spacing ribs 44 with the lower end of the drill collar, while downward displacement is prevented by engagement of the external shoulder 43 on the bearing assembly sleeve 42 with the internal shoulder 15a of the core bit. Suitable packing rings 46 pack off between the extreme lower end of the bearing assembly sleeve or casing 42 and the bore 16 of the core bit. It is noted that the spacing ribs 44 also function to axially align the lower portion of the bearing assembly sleeve 42 within the drill collar, and thus, the lower end of the core-receiving barrel 26 is axially aligned with respect to the outer barrel 12.

In use, the apparatus is assembled as shown in Figure 1 with the inner core-receiving barrel 26 supported upon the double set of ball bearings 36 and 37 at its lower portion. The upper end of the core-receiving barrel 26 is maintained in axial alignment within the outer barrel 12 by the annular alignment bearing member 29. As the coring operation is carried out by rotating the drill pipe, outer barrel 12 and core bit 15, the core which is cut moves upwardly within the bore of the inner barrel 26. The inner barrel, being mounted on the upper and lower bearings 36 and 37, may remain stationary, while the outer barrel and core bit rotate. The bearing assembly sleeve 42 has its lower end engaged within the bore of the core bit and this sleeve will rotate with the bit. As is clearly shown in Figure 2, the bearing assembly sleeve 42 and the confining bearing housing 38, which is attached to said

sleeve, are rotated with the core bit and outer barrel. The inner core-receiving barrel 26 remains stationary because of its engagement with the core, and free rotation of the bearing assembly housing and sleeve is possible because of the double ball bearings 36 and 37. Any end thrust which might occur longitudinally of the inner barrel 26 is taken by the bearings 36 and 37, upward thrusts being absorbed by the upper bearings 36 with the downward thrust being upon the lower bearings 37.

After a core has been taken, it is only necessary to disconnect the core bit 15 from the drill collar 13. As the bit is removed, the lower portion of the bearing assembly sleeve 42 is disengaged from the bore 16 of said bit. The entire inner barrel 26, together with the lower bearing assembly, may then be removed through the lower end of the barrel 12 and its drill collar 13. Removal of the barrel 26 results in a removal of the check valve arrangement 28 as well as the vent tube 32 which are secured to the upper end of said inner barrel. Thus, it is possible to retrieve the core without having to break the connection between the drill pipe and the outer barrel 12 at the upper end of said outer barrel. Furthermore, since the main bearing support is at the lower end of the inner barrel 26 and the upper end of said barrel is maintained in axial alignment by a simple annular bearing element, close tolerances in arranging the bearings are not necessary. As illustrated, there may be a substantial distance between the upper end of the valve cage 27 and the lower end of the connecting sub 11. In prior devices, where the double bearing assembly is located at the upper end, the lower end of the barrel must be supported within the core bit and the tolerances must be held fairly close. In the present arrangement, wide tolerances are allowed which simplify manufacturing and reduce costs.

The particular bearing assembly is extremely simple and provides not only for free rotation of the inner barrel with respect to the core bit and outer barrel, but also functions to take care of any longitudinal end thrust in any direction. The bearing housing 38 may be provided with a suitable fitting 47 which would permit lubricant to be directed to the bearings 36 and 37. If desired, the supporting sleeve or casing 42 of the assembly may have a radial port or ports 48 extending through its wall, whereby the drilling fluid or mud which is circulated downwardly between the inner barrel 26 and the outer barrel 12 during the coring operation may enter the interior of the sleeve or casing 42 and function to lubricate the various parts. The bearing assembly and the lower end of the core-receiving barrel 26 are actually supported within the core bit 15 and upward displacement of the parts is prevented by the external shoulders 45 of the spacing ribs 44 which are secured to the exterior surface of the bearing assembly. This makes it possible to readily insert or remove the inner core-receiving barrel 26 by merely removing the core bit 15.

Having described the invention, I claim:

1. In a coring apparatus, an outer barrel, a core bit threaded onto the lower end of said barrel, an inner core-receiving barrel extending axially within the barrel, and a bearing assembly supported within the core bit and including an elongate sleeve extending upwardly and encircling the lower portion of the inner barrel,

bearing means between the sleeve and inner barrel for rotatably suspending said inner barrel within the outer barrel, and means for sealing the space between the sleeve and barrel above the bearing means to protect the bearing means from contact with fluid circulating downwardly around the exterior of the inner barrel.

2. In a coring apparatus, an outer barrel, a core bit threaded onto the lower end of said barrel, an inner core-receiving barrel extending axially within the barrel, and a bearing assembly supported within the core bit and attached to the core-receiving barrel, said bearing assembly extending upwardly to encircle the lower portion of the inner barrel and having means for rotatably suspending said inner barrel within the outer barrel, means within the core bit engageable by the lower portion of the bearing assembly for supporting the assembly and inner barrel, whereby disconnection of the bit from the outer barrel disengages said bit from the lower portion of the assembly, and said assembly and the inner core barrel may be subsequently removed as a unit from the outer barrel through the lower end thereof.

3. A coring apparatus including, an outer tubular barrel, a core bit connected to the lower end of the barrel, an inner core-receiving barrel extending axially within the outer barrel and having an annular projection on its lower portion, a bearing assembly including a tubular member surrounding the lower portion of the inner barrel and also including upper and lower bearing elements within the bore of the tubular member engaging opposite sides of the annular projection, whereby the inner barrel is rotatably suspended on said bearing elements, and means at the lower end of the bearing assembly for engaging the core bit to support said assembly.

4. A coring apparatus including, an outer tubular barrel, a core bit connected to the lower end of the barrel, an inner core-receiving barrel extending axially within the outer barrel, an external annular projection on the lower portion of the inner barrel and having its upper and lower surfaces forming bearing raceways, bearing elements on said raceways, and a confining housing surrounding the inner barrel and confining said bearing elements on their respective raceways, means for mounting the housing against displacement from the inner barrel, and means for supporting the housing within the outer barrel, whereby the inner barrel is rotatably suspended within the outer barrel by means of said bearing elements and housing.

5. A coring apparatus including, an outer tubular barrel, a core bit connected to the lower end of the barrel, an inner core-receiving barrel extending axially within the outer barrel, an external annular projection on the lower portion of the inner barrel and having its upper and lower surfaces forming bearing raceways, bearing elements on said raceways, a confining housing surrounding the inner barrel and confining said bearing elements on their respective raceways, means for mounting the housing against displacement from the inner barrel, and means for supporting the housing within the outer barrel, whereby the inner barrel is rotatably suspended within the outer barrel by means of said bearing elements and housing, and an aligning means carried by the upper portion of the inner core-receiving barrel for maintaining the inner barrel in axial alignment within the outer barrel.

6. A coring apparatus as set forth in claim 2,

together with bearing means at the upper portion of the inner core-receiving barrel for axially aligning said inner barrel within the outer barrel.

7. A coring apparatus as set forth in claim 4, wherein the means for supporting the housing within the outer barrel comprises an internal shoulder within the core bit engageable by the lower end of the housing, and also wherein said housing is formed with an external projection which engages the lower portion of the drill stem for limiting upward displacement of said housing relative to the drill stem to thereby limit upward axial movement of the inner barrel relative to the outer barrel.

8. A coring apparatus as set forth in claim 4, together with a packing means interposed between bearing housing and the inner core barrel for packing off between these parts above the bearing elements.

9. A coring apparatus as set forth in claim 4, wherein the supporting means for the bearing housing comprises an external shoulder at its lower portion which is adapted to engage and rest upon an internal shoulder in the core bit, whereby when the bit is disconnected from the outer barrel its external shoulder disengages the bearing housing and said housing and inner barrel may be removed as a unit from the outer barrel through the lower end of said outer barrel.

10. A coring apparatus including, a drill stem, 30

a core bit connected to the lower end of the drill stem, a core-receiving barrel mounted axially within the lower portion of the drill stem, a bearing assembly surrounding the lower portion of the core receiving barrel for rotatably supporting the lower end of the core barrel, means mounting the bearing assembly against displacement from the core-receiving barrel, means on the core bit engaging the lower bearing assembly to maintain 5 said assembly in position supporting the lower portion of the barrel, disconnection of said bit from the drill stem permitting the bearing assembly and core barrel to be removed as a unit from the drill stem through the lower end of said 10 drill stem, and an annular bearing element surrounding the upper portion of the barrel for maintaining said upper portion in axial alignment with the drill stem.
